UNITED STATES PATENT OFFICE.

HOWARD L. TREICHLER, OF NEWFANE, NEW YORK.

COIN-CONTROLLED APPARATUS.

Application filed June 29, 1925. Serial No. 40,212.

This invention relates to a coin controlled mechanism and is primarily intended to be used in connection with a vending machine, and is more particularly intended to be used in connection with the vending machine described and claimed in my co-pending application, Serial No. 94,437 filed March 13, 1926 which is designed to vend fruit and other relatively large commodities.

It is, therefore, the object of this invention to provide a mechanism of this character which, by the co-operation of a proper coin will enable the necessary power to be transmitted to the vending mechanism to positively discharge the relatively large articles which the machine dispenses.

Further objects are to provide a coin controlled mechanism which is of simple construction and composed of few parts, which will operate reliably and positively and is not liable to get out of order by the use of an improper coin, or other improper handling of the machine which is liable to occur in machines of this character.

A still further object is to provide a simple and effective mechanism for detecting coins of a smaller size than the coin by which the machine is designed to be operated, and throwing the same out of the operating system before it can co-operate with the mechanism and operate the vending machine.

In the accompanying drawings:—

Figure 1, is a fragmentary front elevation of the coin controlled mechanism, coin chute, improper coin detector, and the coin receiving receptacle.

Figure 2, is a side elevation thereof.

Figure 3, is a fragmentary side elevation of the coin controlled mechanism showing the coin wheels or locking disks in section.

Figure 4, is a view similar to Fig. 3 showing the coin wheels turned to a different position and showing the coin being discharged from between the coin wheels.

Figure 5, is a fragmentary vertical section through the controlling shaft showing the rear coin wheel in elevation, the lower end thereof, being broken away on line 5—5, Fig. 4, and showing the coin receiving recess.

Figure 6, is a fragmentary top plan view of the coin wheels showing the same in proper position to receive a coin.

Figure 7, is a front elevation thereof showing the operating shaft in section.

Figure 8, is a view similar to Fig. 6 showing a coin in interlocking engagement with said coin wheels.

Figure 9 is a fragmentary side elevation of the coin wheels in the position shown in Fig. 8.

Similar characters of reference indicate like parts throughout the several views.

In its general organization this invention comprises an operating shaft which is a part of the vending mechanism to be controlled upon which shaft is secured a driven coin wheel; a freely rotatable driving coin wheel which is mounted on said shaft adjacent the driven coin wheel and is turned by the operator by means of a handle or crank; a coin chute adapted to feed a coin between said coin wheels in such a position that it forms a key and compels the coin wheels to move together, and a laterally movable locking pin mounted in the driven coin wheel and adapted upon moving the driven coin wheel forwardly to be forced into locking engagement with the driving coin wheel by a circular cam guideway which it engages, and which guideway maintains the interlocked engagement of the locking bolt and the driving coin wheel until the coin wheels have turned a complete revolution and return to their normal position.

The vending or dispensing mechanism, which forms no part of the present invention, and is consequently not illustrated in the accompanying drawings, may be of any suitable form and is preferably contained in an enclosing casing or shell 16 which also serves as a support for several of the parts of the coin controlled apparatus. Projecting outwardly from this enclosing casing or shell is the controlling shaft 17 which is connected at its inner or rear end with the vending or dispensing mechanism within said casing in any suitable manner, it being the intention, in the present case, that one complete revolution of this controlling shaft will operate successively to discharge the com-

modity to be sold, release the discharging means, and bring the parts back into position to discharge another article.

The driven coin wheel 18 is vertically disposed and is secured on the outer or projecting end of the horizontal controlling shaft 17, so as to turn therewith preferably by means of a set screw 19 arranged in the rearwardly projecting hub 20 of said driven coin wheel and adapted to engage the controlling shaft as shown in Fig. 3. This driven coin wheel is spaced from the casing or shell 16, and is provided with a vertical plane front face 21 for a purpose which will 10 presently appear.

In front of the driven coin wheel 18 a sleeve 22 is provided on the controlling shaft which is freely rotatable thereon and supports the driving coin wheel 23 which is secured on the rear end thereof adjacent the driving coin wheel in any suitable manner as by a set screw 24 passing through the forwardly extended hub thereof. In order to retain the sleeve 22 and driving coin wheel 25 23 on the shaft and in a proper position relative to the driven coin wheel, the driven shaft is provided with a reduced threaded end 25 on which is screwed a retaining nut 26 which limits the forward movement of 30 the sleeve 22. This nut also serves to retain the operating handle or crank 27 in place, this operating handle having a socket at its inner end which engages the outer end 28 of the rotatable sleeve 22, the same being 35 locked so as to turn together by a key 271.

The driving coin wheel 23 is of substantially the same diameter as the driven coin wheel, and the vertical rear face 29 thereof, is plane or flat similar to the front plane 40 face 21 of the driven coin wheel. These coin wheels are arranged closely together so that the flat faces of both coin wheels co-operate with each other, but unless a coin is inserted in the apparatus, the driving coin wheel is 45 freely rotatable independently of the driven coin wheel, and the turning of the handle or crank 27 does not move the driven coin wheel and thereby not affect the vending mechanism (not shown).

50 In order to couple these coin wheels so as to move together and operate the vending mechanism, each of the flat co-operating faces of both coin wheels is provided with a recess 30 which is extended inwardly from the periphery of each of the wheels a distance substantially equal to the diameter of the coin by which the apparatus is intended to be operated. The depth of each of these recesses from the face of the coin wheel is 55 substantially equal to one half the thickness of the coin, and the length of the same along the periphery of the coin wheel is substantially greater than the diameter of the coin, so that when the coin wheels are turned into

a position in which these recesses register 65 with each other, the said recesses together form a pocket extending inwardly from the peripheries of the coin wheels, which pocket is adapted to receive a coin in an edgewise position which coin acts as a key and compels the coin wheels to move together, as best 70 illustrated in Fig. 8.

In the normal position of the parts the coin receiving recess 30 of the driven coin wheel 18 is arranged at the upper end of the 75 wheel, as shown in Fig. 1, and the coin receiving pocket is consequently formed at this point when the operator of the apparatus turns the crank and the driving coin wheel connected therewith so that the coin receiving recesses of both coin wheels register. The means for feeding a coin into said pocket in proper position to operate the apparatus is therefore arranged at the upper end of the coin wheels and comprises a vertically 80 disposed inclined coin chute 32, the discharge end 33 of which preferably conforms to the peripheral curvature of the coin wheels and is arranged slightly above the coin wheels, as shown in Figs. 1 and 12 and is adapted 85 to register with the coin receiving pocket. This coin chute may be of any approved construction but is preferably made of sheet metal and is of rectangular shape in cross section, the horizontal dimensions of the interior conduit or passage 34 thereof being substantially equal to the diameter and thickness of the proper coin. The chute is 90 preferably supported from the casing or shell 16 by two or more brackets 35 to which 95 the chute can be soldered or otherwise suitably fastened.

When a proper coin is inserted in the upper end 36 of the chute 32, the same slides 100 down the chute past an improper coin detector indicated at 37, to the coin wheels. If the driving coin wheel 23 is not at this time in such a position that its recess 30 registers with the corresponding recess of the driven coin wheel 18, the coin is arrested at the lower end 33 of the chute by the periphery of the driving coin wheel. The operator 105 then turns the crank until the recess of the driving coin wheel registers with the corresponding recess of the other coin wheel, and the coin drops into the pocket into interlocking engagement with both coin wheels. Further turning of the crank therefore turns 110 both the coin wheels, and operates the vending mechanism up to the point where the coin receiving pocket is inverted as in Figures 115 4 and 5 and the coin drops from the same into a coin receptacle or box 38 which is arranged below the coin wheels and is preferably removably supported on brackets 39 which extend forwardly from the vending mechanism enclosing casing.

120 Means are provided which are adapted to

maintain the locked relation of the coin wheels for a complete revolution of the same after the coin has dropped from the pocket, said means also serving to hold the driven 5 coin wheel 18 in its normal position i. e., that position in which its recess 30 is arranged under the coin chute, and also serving to prevent retrograde movement of the coin wheels, which means in their preferred 10 form are constructed as follows:—

The numeral 40 represents a circular guide way mounted in rear of said coin wheels and concentric therewith and having the form of a split ring, the ends 41 and 42 of which 15 ring are offset laterally relatively to each other, and form a spiral or cam guide way having an inclined portion 43 which inclines toward the coin wheels 18 and 23 in the direction of their forward movement. This 20 split ring or guide way may be supported in any suitable manner but is preferably rigidly mounted at its rear side on brackets 44 which are secured at their rear ends to the vending mechanism enclosing casing 16 by 25 bolts 450 or other suitable fastenings. The forwardly inclined portion 43 is arranged adjacent the rearwardly offset end 41 of the guide way, and the front face 45 of the forwardly projecting portion thereof is preferably 30 flat and parallel with the coin wheels and terminates in the front end 42 for a purpose which will presently appear.

The driven coin wheel 18 is provided with a guide way 46 adjacent its periphery and 35 immediately in front of the split cam ring 40 which guide way extends laterally through this coin wheel and is adapted to slidably support the shank 47 of a locking pin, which pin extends laterally rearward from said wheel and is provided with a head 48 at its rear end adapted to engage the front face of said ring. Engagement of the head of this pin with the split ring is maintained by a spring 49 which surrounds the 40 shank thereof and bears against the front side of the head and the rear face of the driven coin wheel 18 and yieldingly holds the pin rearwardly in engagement with the front face of the circular guideway. This 45 pin is located at such a point along the periphery of the driven coin wheel 18 that when the recess 30 thereof is in its normal position at the upper end of the wheel and below the coin chute 32, the head of the pin 50 bears against the rearwardly offset end 42 of the circular guide way, as best shown in Fig. 2. In the drawings this pin is shown as arranged in advance of the coin receiving recess 30 and the offset ends 41 and 42 of the 55 circular guide way correspondingly arranged at the right hand side looking rearwardly, but any arrangement of these parts is satisfactory in which the above named relation is maintained.

60 In order to permit the locking pin to move

forwardly into locking engagement with the driving coin wheel, the front end of the same is rounded and the driving coin wheel 23 is provided with an opening 50 extending laterally therethrough, which opening is arranged slightly in advance of the guide way 46 of the driven coin wheel 18 when the wheels are locked together by the coin, and receives the rounded front end of the shank 47 of the locking pin which moves or crowds the driven coin wheel slightly forwardly relative to the driving coin wheel and thereby loosens the coin in the pocket.

As the coin wheels are moved forwardly by reason of the interlocking engagement of the coin as previously described, the locking pin is forced along the inclined portion 43 of the circular guide way, and since this portion inclines forwardly toward the coin wheels the locking pin is moved longitudinally forward against the compression of the spring 49 into the opening 50 of the driving coin wheel 23 and the coin is loosened by the cam action of the same. The coin wheels are, therefore, positively locked together by this pin, and as the same are therefore turned the coin receiving pocket is inverted, as shown in Figs. 4 and 5, and the coin loosened by the cam action of the rounded end of the locking pin 47 is free to fall down into the coin receiving receptacle or box 38. The head 48 of the locking pin is at this time held in engagement with the flat front face 45 of the circular guide way, and the pin is therefore held in locked engagement during the continued forward movement of the coin wheels up to the point where the pin passes beyond the forwardly offset end 42 and is forced by the spring 49 against the rearwardly offset end 41 and out of engagement with the driving coin wheel 23, in which position the apparatus is in its normal position and is ready to receive another coin, and repeat the operation.

By arranging the inclined portion 43 adjacent the rearwardly offset end 41 of the circular guide way, the head of the bolt bears against the same when the apparatus is not in operation and is yieldingly held thereby in its normal position against the forwardly offset end 42. By this means, if the coin wheels are turned too rapidly, and the bolt is carried beyond the forwardly offset end of the guide way, the driven coin wheel is brought back into proper relation to the coin chute. It will also be observed that the forwardly offset end 42 forms a shoulder against which the head of the locking pin bears, which shoulder prevents retrograde movement of the coin or locking wheels and insures proper operation of the machine.

Reliable operation of the apparatus is further insured by making the coin receiving recesses 30 of both coin wheels, and particularly that of the driven coin wheel of great-

er peripheral length than the diameter of the coin intended to operate the apparatus, since by this means the coin chute is in proper register with the coin receiving recesses during a substantial range of movement of the coin wheels, which permits of adjusting the apparatus with less accuracy and precision than would otherwise be the case.

The use of coins of larger size or diameter than the coin in conjunction with which the machine is intended to operate is prevented by making the coin chute 32 of such a size that it will only receive coins of the proper size or smaller, and in order to prevent effective use of smaller coins an improper coin detector 37 is provided which is constructed as follows:

On the underside of the inclined coin chute 32 an opening 51 is provided which is arranged centrally of the chute and is of less width than the diameter of a proper coin and thereby provides flanges on both sides thereof which are adapted to support a proper coin at its opposite sides, and prevent the same from falling out of the chute, while smaller coins fall out and drop down past the coin controlled apparatus and into the coin receiving receptacle 38. To further prevent small coins from going down the chute and between the coin wheels, a longitudinal opening 53 is provided on the upper side of the chute opposite the opening 51 above which, on the front side of the chute is pivotally mounted a U-shaped arm 54 in a bracket 55 the depending legs 56 of which arm are arranged on opposite sides of the coin chute.

On the central part of this arm a depending coin ejecting finger 57 is provided which is offset rearwardly relatively to the legs and by reason of the preponderating weight of said legs is yieldingly held across the path of the coins through said chute. By this means the heavier coins of a proper size move the finger out of their path and pass down the chute, whereas smaller coins are thrown out by this finger through the opening 51.

In actual use this coin controlling mechanism, as well as the dispensing mechanism with which the same is associated, is covered by a suitable housing so as to prevent unauthorized persons from tampering with the same. For example the front end of the operating shaft 17 may be covered to prevent turning of the same by any means other than the crank handle 27, such covering being effected by a cap 251 which encloses the front end of said shaft, as shown by dotted lines in Fig. 4 and is secured to the hub of this handle in any suitable manner.

As a whole this apparatus is very simple and inexpensive in construction and is durable and not liable to get out of order. It is also reliable in operation and is difficult

to operate in any manner other than that 65 specified, i. e., by the use of a proper coin.

I claim as my invention:

1. In a coin controlled apparatus, a driven movable member operatively connected to the mechanism to be controlled, a driving 70 movable member arranged adjacent said first named movable member, coin operated means for initially locking said members so as to move together, and locking means actuated by motion derived from said driven member 75 for maintaining the locked engagement of said members.

2. In a coin controlled apparatus, a coin wheel, means for turning said coin wheel, a driven coin wheel operatively connected with the mechanism to be controlled, means for feeding a coin between said coin wheels in such a position that it engages both of said wheels and compels them to move together, locking means actuated by motion derived 80 from said driven coin wheel for maintaining the locked engagement of said wheels, and means releasing said coin subsequent to the operation of said locking means.

3. In a coin controlled apparatus a driving member, a driven member, coin operated means for locking said member so as to turn together, laterally movable locking means mounted on said driven member, and cam means for moving said locking means into engagement with said driving member 90 through motion derived from said driven member.

4. In a coin controlled apparatus, a driving coin wheel, means for turning said driving coin wheel, a driven coin wheel operatively connected with the mechanism to be controlled, means for feeding a coin between said coin wheels in such a position that it engages both of said wheels and compels them to move together, a locking member guided in said driven coin wheel and adapted to be moved into locking engagement with the driving coin wheel, cam means moving said locking member into locking engagement with the driving coin wheel through motion derived from the movement of said driven coin wheel, means releasing said coin subsequent to the operation of said locking member, and means for maintaining the locking engagement of said locking member and driving coin wheel.

5. In a coin controlled apparatus, a driving coin wheel, means for turning said driving coin wheel, a driven coin wheel operatively connected with the mechanism to be controlled, means for feeding a coin between said coin wheels in such a position that it engages both of said wheels and compels them to move together, a locking member guided in said driven coin wheel and adapted to be moved into locking engagement with the driving coin wheel, cam means moving 120

said locking member into locking engagement with the driving coin wheel through motion derived from the movement of said driven coin wheel, means releasing said coin driven coin wheel, 5 subsequent to the operation of said locking member, means for maintaining the locking engagement of said locking member and driving coin wheel, and means for releasing said locking members from engagement with said driving wheel upon the completion of 10 the revolution of said coin wheels.

6. In a coin controlled apparatus, a vertically arranged driving coin wheel, means for turning said driving coin wheel, a driven coin wheel arranged in rear of said driving coin wheel and concentric therewith, said driven coin wheel being operatively connected with the mechanism to be controlled, means arranged at the upper ends of said 20 coin wheels and adapted to feed a coin between said coin wheels in such a position that it engages both of said coin wheels and compels them to turn together, a circular guide way arranged in rear of said coin 25 wheels and concentric therewith and having a laterally inclined portion, a locking pin movably mounted in said driven wheel and extending transversely outward therefrom and engaging said guide way, said pin being moved along the inclined portion of said circular 30 guide way upon turning said driven coin wheel and being moved thereby into engagement with said driving coin wheel, and means releasing said coin subsequent to the 35 engagement of said locking pin with said driving coin wheel.

7. In a coin controlled apparatus, a vertically arranged driving coin wheel, means for turning said driving coin wheel, a driven coin wheel arranged in rear of said driving coin wheel and concentric therewith, said driven coin wheel being operatively connected with the mechanism to be controlled, means arranged at the upper ends of said 40 coin wheels and adapted to feed a coin between said coin wheels in such a position that it engages both of said coin wheels and compels them to turn together, a spiral guide way arranged in rear of said coin wheels and concentric therewith, a locking pin movably mounted in said driven wheel and extending transversely outward therefrom and engaging said guideway, said pin being moved along said spiral guide way upon turning 45 said driven coin wheel and being moved thereby into engagement with said driving coin wheel, means releasing said coin subsequent to the engagement of said locking pin with said driving coin wheel, and spring 50 means interposed between said pin and driven coin wheel, said spring means yielding holding said pin in engagement with said guide way and tending to hold said driven coin wheel in proper relation with 55 said feeding means.

8. In a coin controlled mechanism, a vertically arranged driven coin wheel operatively connected with the mechanism to be controlled, coin feeding means arranged above said coin wheel, said driven coin wheel having a recess on the front face and adjacent the periphery thereof which recess is arranged below said feeding means, in the normal position of said driven coin wheel, a driving coin wheel arranged in front of 70 said driven coin wheel and concentric therewith and having a recess adapted to register with the recess of said driven coin wheel and form a pocket which pocket is adapted to receive a coin from said coin feeding means in such a position that it forms a key and compels said coin wheels to move together, a split ring mounted in rear of said coin wheels and concentric therewith, the ends of which are laterally offset relative to each other and said ring having an inclined portion intermediate its forwardly and rearwardly offset ends which inclines forwardly in the direction of the forward movement of said coin wheels, a locking pin slidably mounted in said driven coin wheel and extending transversely rearward and engaging the front face of said split ring, said locking pin being movable forwardly into engagement with said driving coin wheel, and spring means yieldingly holding said locking pin in engagement with said split ring, whereby upon moving said driven coin wheel forwardly the locking pin is forced up the inclined portion of said ring and thereby moved into engagement with said driving coin wheel, which engagement is maintained until the said locking pin passes beyond the forwardly offset end of said ring and is forced by said spring 90 against the rearwardly offset end thereof.

9. In a coin controlled mechanism, a vertically arranged driven coin wheel operatively connected with the mechanism to be controlled, coin feeding means arranged above said coin wheel, said driven coin wheel having a recess on the front face and adjacent the periphery thereof which recess is arranged below said feeding means in the normal position of said driven coin wheel, a driving coin wheel arranged in front of said driven coin wheel and concentric therewith and having a recess adapted to register with the recess of said driven coin wheel and form a pocket which pocket is adapted to receive a coin from said coin feeding means in such a position that it forms a key and compels said coin wheels to move together, a locking pin slidably mounted in said driven coin wheel and extending transversely rearward, said locking pin being movable forwardly into locking engagement with said driving coin wheel, a split ring mounted in rear of said coin wheels and concentric therewith, the ends of which ring are laterally offset 100 110 115 120 125 130

relatively to each other, and said ring having an inclined portion which inclines forwardly in the direction of the forward movement of said coin wheels, and spring means 5 yieldingly holding the rear end of said locking pin in engagement with said split ring, said inclined portion of said ring being ar-

ranged adjacent the rearwardly offset portion of said ring and co-operating with said spring pressed pin to hold said pin against 10 the end of the forwardly offset end of said ring and thereby yieldingly hold the driven coin wheel in its normal position.

HOWARD L. TREICHLER.
